Primary Examiner — Darlington Ly*Assistant Examiner* — Daniel J Domino(74) *Attorney, Agent, or Firm* — Saidman DesignLaw Group, LLC(57) **CLAIM**

The ornamental design for an display screen or portion thereof with graphical user interface, as shown and described.

DESCRIPTION

The sole FIGURE shows a display screen or portion thereof with graphical user interface showing our new design. The peripheral dot-dash broken line represents a display screen or portion thereof which forms no part of the claimed design. The dashed broken lines within the peripheral dot-dash broken line illustrate portions or features of the graphical user interface which form no part of the claimed design.
